HIGH-FREQUENCY APPARATUS FOR DRY-
ING MATERIALS ELECTROSTATICALLYJohn E. Phillips, Jr., Chester, Pa., assignor to
American Viscose Corporation, Wilmington,
Del., a corporation of Delaware

Application December 24, 1947, Serial No. 793,682

4 Claims. (Cl. 219—47)

1

This invention relates to an improved method and apparatus for drying materials electrostatically, that is, by the impression of high frequency or radio frequency currents thereupon. It is concerned with the evaporation of water or any other vaporizable solvent to effect a drying or a change in moisture content of the material being heated. In this specification and claims, the term "moisture" is intended to refer to any liquid and is not restricted to water.

In the past, when subjecting moist materials to be heated to high frequency electric fields for the purpose of reducing the moisture content or drying the articles, the vapor of water or other solvent frequently would condense on one of the electrodes, generally positioned above or in such proximity to the material being dried that drops of the condensate would drip back upon the material. This effect has the disadvantageous potentialities of producing a non-uniform material because of the local spotting and the arcing caused by the drippings. The arcing frequently produces burning, charring, or fusion locally or generally through the article. To avoid the difficulties associated with condensation, it has heretofore been suggested to provide special heating means for the electrode or electrodes giving difficulty. For example, the electrode has been made in the form of a hollow shell through which hot water, steam, or other heated liquid could be passed. Alternatively, it has been suggested to slope the surfaces of the electrodes that would otherwise give difficulty to assure that the condensate would run off to the side away from the material.

While these expedients of the prior art are effective, they do have certain disadvantages in that the former requires a special source of heat in addition to that provided by the high frequency field and the latter is not always conducive to the production of a uniform electric field between the electrodes.

It is an object of the present invention to provide an improved and much simpler method and arrangement for preventing condensation upon one or more electrodes in a high frequency heating system. It is a particular object of the present invention to provide for heating of an electrode or electrodes to prevent condensation and to derive the power for effecting the heating from the high frequency field itself. Other objects and advantages of the invention will be apparent from the drawing and the description thereof hereinafter.

2

In the drawing,

Figure 1 is a diagrammatic elevation of one embodiment of the invention,

Figure 2 is a plan view of the upper electrode in Figure 1,

Figure 3 is a side elevation, somewhat diagrammatic, of a modification,

Figure 4 is an end view partially in section as indicated by line IV—IV in Figure 3, and

Figure 5 is a similar end view of a modification.

As shown in Figures 1 and 2, the material 3 to be dried is disposed between a lower electrode 4 and an upper electrode 5 within a chamber 6. The electrodes 4 and 5 may be of solid plate material or they may be of foraminous character and are supported by insulating rods 2. For example, they may either be made of plates or discs of copper, aluminum, or other conductive steel, or they may be formed of screens made of such conductive metals. The chamber 6 need not be entirely enclosed as it may serve chiefly the purpose of a guard to prevent passersby from coming into contact with the high voltage equipment. Thus, the chamber 6 may be of a closed box-like container having solid walls, or it may be composed of a screen which would permit visual observation of what takes place therewithin. The screen or box forming the container may be of conductive or non-conductive material, speaking electrically, but is preferably conductive for shielding effect to prevent radiation that would give rise to radio interference.

The lower electrode 4 is grounded as by a line 1, advantageously to the chamber 6 when it is of a conductive material, though, if desired, this may be done by replacing the insulating post 2 by a conductive post. The high potential field is imposed upon the upper electrode 5 through the means of the high frequency current feed line 8 connected to one end of the coupling coil 9, the other end of which is grounded as by line 10, advantageously to the chamber 6 when it is of a conductive shielding material, as shown. High frequency current is introduced into the system from a source thereof, such as a radio frequency oscillator 11 through the means of a coupling coil 12.

So far the apparatus may take any of the conventional forms and it is customary to turn back the edges of the electrodes as indicated at 13. In order to heat the electrode 5 which would otherwise be subject to condensation troubles, one or more resistance elements 14 are provided in the field adjacent the electrode 5. Since the effective portion of the field, insofar as the heating

of the material 3 is concerned, extends between electrodes 4 and 5, the portion of the field above the electrode 5 may be considered a stray field and when the resistance is positioned in this portion of the field, as shown, it derives power which would ordinarily be wasted or dissipated without useful function. However, the resistance element or elements may be disposed in any portion of the field provided it is sufficiently close to the electrode 5 to radiate the desired amount of heat thereto. As specifically shown in Figure 2, several resistance elements 14 are stretched across between the in-turned edges of the electrode 5 where they may be conveniently secured in any way desired. Thus, they may be welded thereto or they may merely be hooked about one of the edges of the screen forming the electrode.

In Figures 3 and 4, a modification is shown in which the material to be dried is conveyed continuously by means of a belt 15 serving also as one electrode of the high frequency heating system. This belt may be in the form of a conductive screen grounded by lead line 7a connected to a brush 16 which bears against the belt as it passes thereover. The belt may be driven by sprockets or rollers 17 and passes through the lower portion of a chamber 6a which may be formed without end walls and merely of screened walls, top, sides, and bottom, to facilitate visual observation of the drying operation. Insulating rods 2a suspend the upper electrode 5a from the top of the chamber. The lead line 8a is connected to the upper electrode 5a and a plurality of resistance elements 14a are stretched from one side to the other of the upper electrode 5a. If desired, an additional electric heating element may be provided for the lower electrode in the form of an electric heater 18 connected by means of the lead lines 2b to a source of direct or alternating current of low voltage, such as 110 volts, indicated at 19.

In Figure 5 there is shown a modification in which the resistance element 14b is not connected conductively to the electrode as in Figures 1 to 4 except at one end which is secured to a metallic bar 21 held in place by a stop 22 projecting from the electrode and the downwardly bent edge 23 of the electrode itself. The other end is secured to an insulating bar 24 held back of the stop 25 and the in-turned end 26 along the other side of the electrode. The ends of the resistance coils away from the conductive bar 21 are secured to a common metallic bus bar 27 which is connected by a flexible lead line 28 and a sliding conductive contactor 29 to the high frequency feed line 3b. The slide contactor 29 is movable along the feed line 3b to adjust the drop in potential to which the resistance coils or elements are subjected. This adjustment can be made by loosening the set screw 30 within the contactor 29.

Any conventional source of high frequency current can be employed. The voltage of the high frequency field may vary from 3,000 to 11,000 and even up to 25,000 volts, whereas the frequency may be from 1 to 50 or more megacycles. The value of the resistance and the number of resistances disposed along an electrode depends entirely upon the particular electrical system and the conditions under which evaporation is effected. Thus, the equipment may be employed for the evaporation of water or any other solvent at atmospheric pressure, in which case a temperature of at least 212° F. in the case of water, or the boiling point in the case of the

other liquids, must be maintained upon the upper electrode. A single resistance element may be sufficient to provide the necessary heating and it may either be heated to a glow or to a temperature below glowing conditions. Alternatively, it may generally be preferred to distribute a number of resistance elements as indicated in Figure 3 of the drawing to more uniformly distribute the heat to the adjacent electrode. For example, in the embodiment of Figure 3, where water is being evaporated at atmospheric pressure from water-wet cakes of rayon, six transverse elements may be uniformly spaced longitudinally of the electrode, or a greater number of resistance elements may be disposed at the end of the upper electrode below which the cakes first are heated than at the discharge end of the system. Each of such elements may have a resistance between 5 to 30 ohms illustratively, and the heat developed and radiated to the electrode is sufficient to raise the temperature of the electrode throughout its length so as to prevent condensation difficulties.

The method and apparatus of the present invention can be employed for the vaporization of any liquid from any article, such as an annular package, at atmospheric pressure. Or, by making the chamber 6 tight, such removal can be effected under high vacuums even up to a vacuum of 25 inches of mercury or under super-atmospheric pressure, such as up to 2 or 3 atmospheres. The radio frequency heating may be employed for reducing the moisture content to any predetermined extent. For example, in drying regenerated cellulose rayon in the form of wound packages, such as annular "cakes" collected in centrifugal buckets, the moisture content may be reduced from an initial figure of 180 to 200% down to less than 80% in a very brief period such as from 3 to 20 minutes while being subjected to radio frequency and thereafter the balance of the moisture may be removed by conventional oven drying systems in which heated air is circulated past the cakes. In such an event, the partially dried materials may be subjected to higher temperatures in the oven drying than would ordinarily be permissible and the control of the humidity is generally not so critical. For example, a package of rayon reduced to about 80% moisture content can be subjected to heated air at a temperature of 180 to 210° F. as compared to the usual 140° F. heretofore practiced.

The method and apparatus may be employed with particular advantage in the drying of wet spun artificial filaments made of regenerated cellulose, cellulose acetate, vinyl resins, casein, or the like. It may also be used with advantage for the drying of annular wound packages (without a central core) of felts and fabrics, which may be employed for the removal of the solvent in the case of the sizing, coating, dressing, or otherwise conditioning of yarns, fibers, fabrics or the like. For example, it may be employed for removing the solvent from tire cords which have been impregnated with rubber coating materials, from yarns impregnated with solutions, dispersions, or emulsions of weaving and knitting sizes, as well as sizes used for setting the twist of lively twisted yarns; for removing the solvent from materials which have been subjected to crease-proofing or other finishing materials. It may also be used for the removal of organic solvents, such as acetone, which have been applied to render potentially adhesive fibers.

tacky in yarns, fabrics, felts, papers, and the like, and particularly when such articles are extremely thick. In such operation, the material, after treatment with the solvent to activate the fibers to the tacky condition, is wound and the wound package is passed through the drier of the present invention and, after removal of the solvent, the tacky fibers bind together with themselves and/or with other non-adhesive fibers that may be present in the article subjected to the solvent whereby the resulting article has increased coherence and strength.

It is to be understood that the description herein is entirely illustrative and changes and modifications may be made without departing from the spirit and scope of the present invention as defined in the appended claims.

I claim:

1. Apparatus comprising spaced electrodes, means for impressing a high frequency current across the electrodes, and a resistance element disposed in the field adjacent one of the electrodes receiving current exclusively from the field to heat the electrode thereby, at least one end of the element being connected conductively to the electrode.

2. Apparatus in accordance with claim 1 in which one electrode is grounded and a high potential is impressed on the other by a high frequency feed line, and the resistance element is disposed adjacent the high potential electrode for heating it.

3. Apparatus in accordance with claim 1 in which one electrode is grounded and a high potential is impressed on the other by a high frequency feed line, and the resistance element is disposed adjacent the high potential electrode for heating it and is conductively connected at both ends to the high potential electrode.

4. Apparatus in accordance with claim 1 in

which one electrode is grounded and a high potential is impressed on the other by a high frequency feed line, and the resistance element is disposed adjacent the high potential electrode for heating it and is conductively connected to the high potential electrode at one end and at the other end is connected to the feed line at a position spaced from the juncture of the feed line with the electrode.
